UNITED STATES PATENT OFFICE.

JOHN C. TORREY, OF ATTLEBORO, MASSACHUSETTS, ASSIGNOR TO F. L. TORREY & COMPANY, OF ATTLEBORO, MASSACHUSETTS, A COPARTNERSHIP COMPRISING FRED L. TORREY AND JOSEPH KERKHOFF.

BUCKLE.

1,366,104.

Specification of Letters Patent. Patented Jan. 18, 1921.

Application filed January 22, 1920. Serial No. 353,239.

To all whom it may concern:

Be it known that I, JOHN C. TORREY, a citizen of the United States, and resident of the city of Attleboro, in the county of Bristol and State of Massachusetts, have invented certain new and useful Improvements in Buckles, of which the following is a specification.

This invention relates to buckles of the class more particularly adapted to automatically grip and bind a belt in adjusted position about the body of the wearer; and the object of this invention is to provide a simple and practical cam-shaped clamping member which will present a rounding biting surface to the belt to bite the same against the back of the front plate to prevent the same from slipping.

By my improved construction of buckle the same is adapted to operate upon widely different thicknesses of belts.

With these and other objects in view, the invention consists of certain novel features of construction, as will be more fully described, and particularly pointed out in the appended claims.

In the accompanying drawing:

Figure 1—is a sectional side elevation illustrating my improved cam-bar as mounted in a buckle.

Fig. 2—is a sectional side elevation of my improved cam-bar, showing the pivoting members formed integral therewith.

Fig. 3—is an enlarged view showing a portion of the buckle with the cam-bar in section and in position to grip and bite the belt against the inner end of the front plate of the buckle.

Fig. 4—is a perspective view of my improved cam bar.

Fig. 5—is a perspective view of the buckle, showing the rear side thereof.

It is found in practice that the ordinary clamping bar which is constructed with a thin, clamping blade, is capable of acting properly upon a belt of a given thickness. Then again the sharp, narrow edge of such a clamp cuts and in time destroys the belt.

To obviate these difficulties I have provided a pivotally-mounted, cam-shaped, gripping-bar which presents a rounding, gripping surface to the belt, and by which construction a belt of any thickness within

reasonable limits, may be used and firmly held in this buckle. 55

The buckle I have constructed has the usual face-plate 10 with two rearwardly-extending side walls 11. In these side walls I have pivotally mounted my improved cam-shaped, gripping-bar 12, which is preferably formed of sheet stock folded into somewhat of a tubular form having a relatively large, inner loop 13 and a smaller, outer loop 14, on opposite sides of its pivoting point 15. This inner loop is formed by bending the sheet stock from this pivoting point around in a circular form, providing a substantially, cam-shaped, inner portion whose engaging or biting surface is roughened or corrugated as at 16, to engage the belt end 17, to bite the same against the inner face of the front plate 10. The sheet metal forming the outer loop 14 is folded into the form of an eye 18 in which the bail member 19 is pivotally held. 75

The edge 20 of the stock which forms this outer eye, extends around to abut against the back portion 21 thereof, while the edge 22 of the stock forming the inner loop abuts against the edge 20 of the outer loop by 80 which construction it will be seen that the edge 22 of the inner loop serves to support the inturned edge 20 of the outer loop from opening under any severe strain which may be applied to this outer loop through a 85 tension on the belt portion 23 which is secured to the bail 19.

In other words if there is any spring in the stock the harder the biting-loop presses against the belt the greater the supporting pressure of its edge 22 against the edge 20 of the eye where the strain is applied. 90

By my improved construction it will be noted that the biting surface of the cam-bar is round in cross section and therefore presents a relatively-broad and biting surface to the belt which grips and binds the same without cutting or injuring it. 95

My improved form of gripping bar has a number of advantages over other fastening means of this character; among others being; first, that the bar may be constructed of sheet metal and folded into cam shape which in the using of plated material will bring the precious metal on the exposed or 100 outside thereof, the base metal surface being 105

entirely inclosed; second, by forming my improved bar of sheet stock it may be folded into the exact shape desired having inner and outer loops and may be completed without the use of solder, which is of great advantage from a practical standpoint; third, the pivoting members may be formed integral with this bar again obviating a soldering operation and reducing the expense of construction; fourth, by this construction the clamp is formed very light in weight and no stock is wasted and the same is much less expensive to construct than would be possible if the bar were made of solid stock, fifth, by forming this clamping member in cam-shape it will adapt itself to belts of any thickness and as the bail is pivoted in the clamp it insures a straight pull from the eye of the clamp at whatever angle the biting portion of the clamping member may stand.

10 My improved form of buckle is very simple and practical in construction and effective in its operation.

15 20 25 The foregoing description is directed

solely toward the construction illustrated, but I desire it to be understood that I reserve the privilege of resorting to all the mechanical changes to which the device is susceptible, the invention being defined and limited only by the terms of the appended claim.

I claim:

A belt buckle comprising a body portion having a front plate with rearwardly-turned 35 edge walls, a clamp member formed of sheet metal having one edge folded to form a clamp cam and its opposite edge folded to form a bail-receiving pivot eye, integral laterally-extending trunnions on said clamp 40 member positioned intermediate said cam and clamp eye and pivoted in said side walls, said cam portion serving to grip the belt against the inner face of said body, and a bail pivotally connected to said bail eyes to 45 which the opposite end of the belt may be attached.

In testimony whereof I affix my signature.

JOHN C. TORREY.
